United States Patent Office.

CHAUNCY GRAHAM, OF ELIZABETH, NEW JERSEY.

Design No. 4,844, dated April 25, 1871.

DESIGN FOR THE FRONT OF A COUNTRY HOUSE.

The Schedule referred to in these Letters Patent and making part of the same.

To all whom it may concern:

Be it known that I, CHAUNCY GRAHAM, of Elizabeth, in the county of Union and State of New Jersey, have invented a new and improved Design for the front of a Country House; and I do hereby declare the following to be a full, clear, and exact description thereof, which will enable those skilled in the art to make and use the same, reference being had to the accompanying drawing forming part of this specification, which drawing represents a front elevation of a country house ornamented according to this invention.

The principal features of my design are the arcs on the sides and the gable-shaped cornice on the top of the main attic windows in a house with a French roof, the edges of the roof being curved to correspond to the side arcs of said main attic windows. The side attic window is surmounted by an arched cornice.

In the drawing—

The letter A designates the front of a house which is provided with a French roof, B, and with attic windows C D.

The side attic window C is ornamented by an arched cornice, E, with its ends projecting inward.

The main attic windows D are situated under the gable-shaped cornice F and between the arcs G, which extend from the gable-shaped cornice F down to the main cornice H.

The edges I of the roof are convex, to correspond to the arcs G on the sides of the main attic windows.

By the arcs G and the gable-shaped cornice F, a novel and rich appearance is given to the front of the house.

What I claim as new, and desire to secure by Letters Patent, is—

1. The arcs G on the sides of the main attic windows D, as shown.

2. The gable-shaped cornice F over the attic windows D, as shown.

3. The combination of the arcs G and gable-shaped cornice F, as shown.

CHAUNCY GRAHAM.
